UNITED STATES PATENT OFFICE.

EDWIN WILDT, OF LEICESTER, ENGLAND, ASSIGNOR TO WILDT & CO. LIMITED, OF LEICESTER, ENGLAND, A BRITISH COMPANY.

STRIPING MEANS FOR KNITTING MACHINES.

Application filed February 16, 1922. Serial No. 536,919.

To all whom it may concern:

Be it known that I, EDWIN WILDT, a subject of the King of Great Britain, residing at Leicester, in the county of Leicester, 5 England, have invented new and useful Improvements in or Relating to Striping Means for Knitting Machines, of which the following is a specification.

This invention relates to circular knitting machines more especially of the type employed for producing seamless stockings and socks, and concerns striping means therefor as will be hereinafter described.

The object of the invention is an improved form and arrangement of means for producing vertical stripes or vertical patterns, such as in the leg and instep or foot of the knitted article, the main feature being to enable a large variety of patterns to be 20 formed.

In circular machines which, for making seamless heels and toes, are capable of operating with an oscillating motion, it is already well known to use mechanism for producing continuous vertical stripes such as by 25 means of one or more coloured yarns. The present invention comprehends means in machines of this kind which can either be used to make continuous stripes in the known manner or can be used to produce an interrupted, intermittent or broken stripe, or a 30 smaller pattern such as spots, distributed longitudinally in the knitted tube.

To this end means are furnished to control the action of the striping needles so that 35 during knitting of the tube of fabric said needles may be brought into and out of action as required, thus enabling the stripe or pattern produced by said needles to appear in such form as may be prearranged.

It is also a feature of the invention that not only may the striping needles as a whole be controlled if desired, but the improved mechanism enables certain of the said 45 needles or certain series of the said needles to be controlled independently of the others whereby a large variety of pattern effects may be obtained.

The method of striping or patterning to 50 which the present invention is applicable is that wherein the needles take two yarns when no pattern is to be formed and miss one of said yarns when they are to form a stripe or pattern. The needles capable of missing one yarn are hereinafter termed

striping needles. The yarn missed by the needles is thrown to the back of the fabric while the remaining yarn is knitted and appears on the face of the fabric in contrast to the non-patterned parts.

The means comprising the invention operate to select out from the complement of striping or patterning needles those which are to miss the yarn and to operate said selected needles in such a manner that they will not take the yarn for one or a predetermined number of courses thereby producing a pattern by the other yarn the continuity of which can be broken by causing said needles to take both yarns.

Broadly the invention consists of an arrangement wherein the striping needles have butts of different length, and a cam is movably arranged so as to act upon the different butts when it occupies different positions. The function of the cam is to depress the selected needles so that they miss the yarn not required for striping. By means of the arrangement just mentioned the cam may be moved to various positions to act upon pre-arranged needles among the striping needles when a pattern is to be formed.

According to the preferred arrangement, the cam is movable both horizontally and vertically, the latter movement being used to bring the cam into and out of action, while in a horizontal direction it can be moved to different positions for acting upon butts of different lengths on the striping needles.

For example, the striping needles may be furnished at the lower end of the stem with a butt to be engaged by the movable cam the butts of some of the needles being longer than those of the others. In one position the cam will engage only the long butts, while in another position it will engage both the long and the short butts. In this arrangement the cam is moved upwards to miss all the butts.

A concrete embodiment of the invention is shown in the accompanying drawings, wherein:

Figure 1 is a front elevation of part of a circular knitting machine having the invention applied thereto.

Figure 2 is a plan of the same.

Figure 3 is a side elevation viewed from the right of Figure 1.

Figure 4 is an inside elevation of the means for actuating the movable cam.

Figure 5 shows said means in vertical section.

Figure 6 is an inside elevation of the bracket and movable cam.

5 Figures 7, 8 and 9 are plan views of the mechanism of Figure 6 and show the parts thereof in different positions.

Figure 10 is a section on line 10—10 of Figure 7.

10 Figure 11 is a section on line 11—11 of Figure 7.

Figure 12 is a section on line 12—12 of Figure 7.

15 Figure 13 is a section on line 13—13 of Figure 8.

Figure 14 shows two striping needles having butts of different length.

Figures 1 to 3 are drawn to a smaller scale than the remaining figures and 20 throughout the drawings like parts are designated by the same reference characters.

the cam 2 is moved outwards by a spring actuated plunger 21 (Figures 7 and 8) which acts against a lip 22 on the slide. The slide is moved inwards by passage of its outer edge 23 in contact with a cam plate 24 (Figures 1 to 5) arranged in the block 14 and moved to different horizontal planes by a lever 25 from the pattern chain 18 in similar manner to the other cam plate 13 already described.

75 To hold the slide plate 7 and the slide 3 in the inward position after they have been pressed in by the cam plates a locking catch is combined with each. These catches are indicated at 26 and 27 (Figures 7, 8, 11 80 and 12) and consists of cams mounted to turn on a pin 28 each under the influence of a spring plunger 29. Each locking catch has a nose 30 which when its slide is pressed inwards moves behind a projecting part 31 85 thereon as shown in Figure 8 and prevents

bring the cam into different positions for acting on butts of different length on the striping needles.

2. In a circular knitting machine, striping means comprising striping needles having butts of different length thereon, a cam movable both horizontally and vertically, the latter movement being used to bring the cam into and out of action, and the horizontal movement being used to bring the cam into different positions for acting on butts of different length on the striping needles, and pattern mechanism to operate and control said cam so that during the knitting of the tube of fabric the striping needles may be brought into and out of action in a prearranged manner to produce a stripe or pattern.

3. In a circular knitting machine, striping means comprising striping needles having butts of different length thereon, a cam for acting upon said butts, a slide upon which said cam is mounted so as to move vertically whereby it is brought into and out of action, a bracket in which said slide is movable horizontally for bringing the cam into different positions for acting on butts of different length on the striping

needles, said cam and slide being spring actuated in one direction, devices to move said cam and slide in the other direction, and pattern mechanism to control said devices.

4. In a circular knitting machine, striping mechanism comprising striping needles having butts of different length thereon, a cam for acting upon said butts, a slide upon which said cam is mounted so as to move vertically whereby it is brought into and out of action, a bracket in which said slide is movable horizontally for bringing the cam into different positions for acting on butts of different length on the striping needles, said cam and slide being spring actuated in one direction, devices to move said cam and slide in the other direction, pattern mechanism to control said devices, and a locking catch which operates automatically in one direction to hold the cam and slide in one of its positions and is moved in the opposite direction by one of the aforesaid pattern controlled devices.

In testimony whereof I have signed my name to this specification.

EDWIN WILDT.
